UNITED STATES PATENT OFFICE.

RODERICK J. M. PARKE AND EDWARD D. BRAND, OF TORONTO, ONTARIO, CANADA.

THERMOSTAT FOR ELECTRIC HEATING AND COOKING APPARATUS.

1,217,994.

Specification of Letters Patent.

Patented Mar. 6, 1917.

Application filed December 19, 1913. Serial No. 807,690.

To all whom it may concern:

Be it known that we, RODERICK JOSEPH MACDONALD PARKE and EDWARD DAVID BRAND, of the city of Toronto, Province of Ontario, Canada, have invented certain new and useful Improvements in Thermostats for Electric Heating and Cooking Apparatus, of which the following is a specification.

10 This invention relates to thermostatic apparatus such as disclosed in United States Letters Patent No. 987161 dated March 21, 1911, and Canadian Letters Patent No. 127074 dated July 26, 1910, and our object 15 is to devise apparatus of this type which will be reliable, easily calibrated and easily set. We attain our object by means of the constructions hereinafter described and illustrated in the accompanying drawings in 20 which—

Figure 1 is a front elevation of our improved apparatus;

Fig. 2 is a front elevation with the dial and hand removed;

25 Fig. 3 is a front elevation illustrating particularly the rocking frame and means for actuating the driven rock shaft from the thermostatic element; and

Fig. 4 is a vertical cross section of the device partly in elevation.

In the drawings like numerals of reference indicate corresponding parts in the different figures.

The thermostatic element may be of any ordinary type, though we show a form in which a tube 1 containing mercury is connected with a coiled Bourdon tube 2 usually filled with a gas. The end of this coiled tube moves to one side or the other on an arc of a circle according to the pressure in the tube 2 due to the expansion or contraction of the mercury. This movement is used to actuate the apparatus in the following manner and by the following means:—

45 A frame 3 is pivoted at 4 on the casing 5 of the apparatus. This frame at its upper end is provided with the lug 6 with which

is engaged the screw 7 passing loosely through the lug so as to be rotatable therein and held from lengthwise movement by the collar 8 suitably held in place on the screw. This screw is threaded through the casing as indicated and its outer end is squared for engagement with a box wrench, by means of which the screw may be rotated to rock the frame 3. Preferably the lug is a separate piece from the frame and secured thereto by means of rivets. On the adjustable frame 3 is journaled the driving rock shaft 10, to which is secured the gear segment 11. This gear segment is connected with the coiled tube 2 of the thermostatic element by means of the link 12, pivotally connected to the end of the tube 2 and adjustably and pivotally connected with the gear segment 11, the pivot pin 13 being adjustably secured in a radial slot 14 in the gear segment in any well known manner. This adjustable connection enables the extent of movement of the gear segment relative to the thermostatic element to be adjusted. This gear segment meshes with the pinion 15 secured to the driven rock shaft 16. A rocking arm 17 preferably yoke shaped and formed of non-conducting material, is journaled concentric with this rock shaft, being secured to the gear wheel 18. This rocking arm is angularly adjustable by means of the gearing 19 meshing with the gear wheel 18, actuated by the spindle 20 journaled in the casing and provided with the milled hand wheel 21 outside the casing below the dial 22. This rocking arm 17 carries the contacts 23 and 24, preferably formed as screws adjustable in the arm. 25 is a spring finger clamped between the upper ends of the yoke shaped arm 17 by means of the screw 26. This spring finger normally contacts with the contact 23. A projection 27 formed on a collar 28 secured to the rock shaft 16 is adapted to engage the finger 25 to force it into contact with the contact 24 as the tube 2 expands under the action of heat and actuates the gear segment 11. The end of the

rock shaft 16 carries the hand 29 which moves over the dial to indicate the temperature to which the thermostatic element is exposed. An index 30 is secured to the arm 17 and serves to indicate the temperature for which the device is set. The operation of the device is as follows:—

Assuming that a certain temperature is to be attained before the spring finger 25 is shifted from its engagement with the contact 23 to engagement with the contact 24, the rocking arm 17 is moved by rotating the hand wheel 21 until the index 30 is opposite the desired temperature as indicated by the scale marked on the dial. This moves the contacts 23 and 24, but the spring finger 25 is still retained in contact with the contact 23. As the position of the spring finger thus varies, its position relative to the projection 27 is varied. As the temperature to which the thermostatic element is exposed rises, the rock shaft 16 is rotated as already described and the projection 27 moved toward the spring finger 25. When the projection engages the spring finger 25, the finger is moved away from the contact 23 and into engagement with the contact 24. Thus any circuit including the contact finger 25 and contact 23 is broken and any circuit including contact finger 24 and spring finger 25 is closed, which is an operation necessary to the heat regulation of the cooking apparatus disclosed in the prior patent hereinbefore referred to. The adjustment of the connection between the thermostatic element and the gear segment 11 and the adjustment of the rocking frame 2 is of considerable importance. The adjustment of the pivot 13 enables me to approximately calibrate the apparatus so that the indications on the dial agrees approximately with the actual temperature to which the thermostatic element is exposed and final fine adjustment being made by adjusting the screw 7. By the arrangement described, we attain satisfactorily the object of our invention as set out in the preamble of this specification.

What we claim as our invention is:—

1. In a thermostatic apparatus the combination of a thermostatic element; a rocking frame; a rock shaft journaled in said frame; means whereby said thermostatic element rocks said shaft; means for rocking and adjusting said frame; a driven rock shaft 55 geared to the rock shaft; a rocking arm journaled concentric with the driven rock shaft; a pair of contacts carried by said rocking arm; a contact finger carried by said rock arm adapted to contact with either 60 contact and normally yieldingly held in contact with one of them; an arm fixed to the driven rock shaft adapted when the shaft is rocked to engage said contact finger to

move it toward the second contact; and means for angularly adjusting the rocking 65 arm.

2. In a thermostatic apparatus, the combination of a thermostatic element; a rocking frame; a driving rock shaft journaled in said frame; a gear segment secured thereto; a pivoted link connecting said thermostatic element with said gear; a driven rock shaft journaled in the frame; a pinion secured thereto meshing with the aforesaid gear segment; a rocking arm journaled concentric with the driven rock shaft; a pair of contacts carried by said rocking arm; a contact finger carried by said rock arm adapted to contact with either contact and normally yieldingly held in contact with one of them; an arm fixed to the driven rock shaft adapted when the shaft is rocked to engage said contact finger to move it toward the second contact; and means for angularly adjusting the rocking arm. 85

3. In a thermostatic apparatus the combination of a casing; a thermostatic element; a frame pivoted adjacent one end on the casing; a screw engaging the casing and frame adapted to rock the latter; a rock shaft journaled on the frame; means whereby said thermostat actuates said rock shaft; a rocking arm journaled concentric with the rock shaft; contact devices carried by said arm; a contact arm carried by the rock shaft and adapted to actuate the contact devices; and means for angularly adjusting the rocking arm. 90

4. In a thermostatic apparatus, the combination of a thermostatic element; a rock- 100 ing frame; a driving rock shaft journaled in said frame; a gear segment secured thereon; a link pivoted to the thermostatic element and having a radially adjustable pivoted connection with the said gear segment; 105 a driven rock shaft journaled in the frame; a pinion secured thereto meshing with the aforesaid gear segment; a rocking arm journaled concentric with the rock shaft; contact devices carried by said arm; a contact arm carried by the rock shaft and adapted to actuate the contact devices; and means for angularly adjusting the rocking arm. 110

5. In a thermostatic apparatus, the combination of a casing; a thermostatic ele- 115 ment; a frame pivoted adjacent one end on the casing; a screw engaging the casing and frame adapted to rock the latter; a driving rock shaft journaled in said frame; a gear segment secured thereto; a link piv- 120 oted to the thermostatic element and having a radially adjustable pivoted connection with the said gear segment; a driven rock shaft journaled in the frame, a pinion secured thereto meshing with the afore- 125 said gear segment; a rocking arm journaled

concentric with the rock shaft; contact devices carried by said arm; a contact arm carried by the rock shaft and adapted to actuate the contact devices; and means for 5 angularly adjusting the rocking arm.

6. In a thermostatic apparatus the combination of a yoke shaped rocking arm of non-conducting material; a contact finger clamped at one end between the parts of the 10 arm; contacts carried by the parts of the arm between which said finger may play;

a shaft from which said arm is supported; a projection on said shaft adapted to engage the finger; and a thermostatic element adapted to rock the shaft.
